The ornamental design for a funnel plate, as shown and described.

DESCRIPTION

FIG. 1 is a front isometric view of a funnel plate in accordance with the new design;

FIG. 2 is a top view of the funnel plate design shown in FIG. 1;

FIG. 3 is a left side view of the funnel plate design shown in FIG. 1, the right side view being a mirror image;

FIG. 4 is a bottom view of the funnel plate design shown in FIG. 1;

FIG. 5 is a front view of the funnel plate design shown in FIG. 1, the back view being a mirror image; and,

FIG. 6 is a side cross sectional view of the funnel plate shown in FIG. 2 along line 6—6.

The sectional view of FIG. 6 is included to clarify the shape of the design, and the broken lines therein form no part of the claimed design.
